UNITED STATES PATENT OFFICE.

JOSEPH E. PHILLIPS, OF WEST ASHFORD, CONNECTICUT.

WINDOW-SHADE.

SPECIFICATION forming part of Letters Patent No. 291,222, dated January 1, 1884.

Application filed December 1, 1883. (No m₂ del.)

To all whom it may concern:

Be it known that I, JOSEPH E. PHILLIPS, of West Ashford, county of Windham, State of Connecticut, have invented a new and useful 5 Improvement in Window-Shades, of which the following is a full, clear, and exact description, reference being had to the accompanying drawings, making part of this specification.

My invention relates to an improvement in 10 window-shades of the class known as "Venetian blinds," and to the means for effecting the adjustment of the same; and it consists in providing the upper slat of the shade with journals removed from its ends, said slat being 15 journaled in and upheld by means of eyebolts secured to and pendent from the upper horizontal beam of the window or shade-frame, leaving said upper slat free to be revolved for bringing it and the other slats which compose 20 the blind to the desired inclination; in the combination, with the said upper slat, of the pulley and endless cord for adjusting the slats; also, in providing the upper slat with a swiveling pulley or pulleys secured to journals on 25 said slat, one of said journals being formed upon or secured to one end of the slat, whereby said pulleys are adapted to remain always in working position, no matter what may be the inclination or position of the slats which 30 compose the blind or shade.

In the accompanying drawings, Figure 1 is 35 a perspective view of my improved window-shade, shown applied to a frame made especially for the purpose and adapted to be attached to any window. Fig. 2 is an elevation of the frame and upper slat, showing the journals formed in the latter, the manner of attaching it to the frame, and the arrangement of the pulleys and cords working thereon; and 40 Fig. 3 is a detail sectional view of the upper journaled slat and one of its supporting eyebolts.

A represents a frame, of any suitable form, by preference being composed, in main, of 45 three timbers, an upper horizontal one, from which the shade is suspended, and two pendent side pieces secured to the ends of the horizontal timbers, serving to protect the edges of the slats and forming a frame, which is adapted, 50 by means of hooks *aa* or equivalent fastenings, to be attached to any window, so that it may be easily removed when desired, and as easily

replaced. It will be apparent, however, that where the user does not desire the shade to be made detachable from the window, the frame 55 A, above described, may be dispensed with, and the shade attached directly to the upper horizontal frame of the window frame or casting. The upper slat, B, of the shade C is provided with journals B' B², removed from the 60 ends, as shown, and adapted to receive and be upheld and suspended from the horizontal timber of the frame A by means of eyebolts or screws *c c'*, secured to said horizontal timber, the eyes or hooks of which form bearings for 65 the journals B' B², whereby the slat B is adapted to be rocked on its journals in said bearings, for a purpose hereinafter set forth; and as a means for rocking slat B, a pulley, D, is securely attached to one end thereof, a 70 cord, D', passing around it, and also around an adjustable pulley, of any preferred form, secured to one of the vertical timbers of the window to which my improved shade is to be applied. The opposite end of slat B to that 75 upon which pulley D is located has a journal formed upon it, (shown at B³), provided with a swiveling-loop, *e*, in the pendent arm of which a pulley, E, is journaled, adapting the slat B to be rocked without disturbing said 80 pulley, which it is desirable to have remain pendent, as shown in the drawings. Other pulleys, E' and E², similar to that E, are employed, also swiveling upon journals B⁴ B⁵, 85 formed upon slat B, over which and the pulley E pass the cords F and F', for elevating and lowering the shade. The slats which compose the shade or blind are suspended and held in place by means of two or more tapes or bands, G, passing entirely around them, as 90 shown, and provided at regular intervals with cords, which pass under each slat, for the purpose of holding all the slats at a uniform distance apart, and at an inclination corresponding with the inclination of the upper and controlling slat, B, which latter, when rocked in its bearings in the eyebolts *c c'*, by means of the cord D' and pulley D, above described, will adjust and regulate the angle of inclination of all the slats which contribute to make up the 100 shade or blind. The slats are each and all, except the upper one, B, slotted at H H, as shown, to permit the passage through them of the cords F F', hereinabove referred to, which

pass around the pulleys E, E', and E'', and being fastened at their lower extremities to the lower slat of the blind, when they are drawn over said pulleys, the lower slat is elevated, 5 and in its ascent carries with it the slats above it, until the blind is raised as high as desired, when the elevating-cords may be wound upon a hook, I, secured to the frame A, and the blind be held in its elevated position.

10 Having now described my invention, what I claim as new is—

1. In a window shade or blind, the broad pivotal upper or end slat, provided with journals removed from its ends, in combination 15 with eyebolts or hooks forming bearings for said journals, substantially as described.

2. In a window-shade or Venetian blind, the broad pivotal upper slat provided with journals removed from its ends, in combination 20 with eyebolts or hooks pendent from the upper horizontal bar, and a detachable frame applicable to the window-frame, for the purpose, and substantially as described.

3. The combination, with the upper slat of a Venetian blind, of a journal at one end, and 25 the swiveling-pulley mounted thereon, substantially as and for the purpose specified.

4. The upper broad pivotal slat provided with two journals removed from its ends, in combination with the journal at one end, having the swiveling-block thereon and the grooved pulley fast on its opposite end, and carrying a cord for adjusting the angles of the slats, substantially as described.

5. The upper broad pivotal slat, B, provided with the journals B', B'', B³, B⁴, and B⁵, in combination with the eyebolts c c', swiveling-pulleys E, E', and E'', fixed pulley D, and the cords D, F, and F', all substantially as and 35 for the purpose set forth.

In testimony whereof I have hereunto set my hand this 28th day of November, A. D. 1883.

JOSEPH E. PHILLIPS.
